UNITED STATES PATENT OFFICE

2,335,866

COKE-OVEN DOOR HANDLING MECHANISM

Paul Howard Lavelly, Pittsburgh, Pa., assignor to
Koppers Company, a corporation of Delaware

Application January 5, 1942, Serial No. 425,699

12 Claims. (Cl. 212—4)

The present invention relates in general to apparatus for handling the doors of horizontal coke ovens and is more specifically concerned with provision of a door-head mechanism that is operative, on either the usual pusher-machine at the pusher-side or on the usual door-machine at the coke-side of such a coke-oven battery, automatically to remove from, and to restore to, latched position in latch-hooks provided for the purpose, cammed oven-door latch-bars that are non-integral with the oven-doors and are of the general type shown, for example, in Joseph van Ackeren's copending application, filed August 13, 1941, Serial No. 406,653.

An object of the present improvement is the provision of a simple and practical mechanism that is adapted to utilize the usual horizontal and vertical reciprocatory movements, required of mechanisms for manipulating coke-oven doors mechanically to effect, in sequence, the unlatching, the supporting, and re-latching of oven-door latch-bars that are not affixed to the oven-doors and that in their effective manipulation demand rotary motion of latching elements about the axes of such latch-bars and movement in a vertical plane independently of the associated coke-oven door.

A further object of invention is the provision of a mechanism that is adapted, in co-operative response to the required movements of apparatus for handling coke-oven doors, in sequence, rotatably to engage coke-oven latch-bars and to turn latching elements therefor about the aforesaid axis of the latch-bars and securely to grasp and elevate said latch-bars from their seats in the latch-bar hooks during the short interval said door-head mechanism is moving into position for grasping and removing a coke-oven door from a coking-chamber, and is also adapted to perform these said operations in the reverse said sequence while the door-head mechanism is moving away from such door after its replacement thereby in the mouth of a coking-chamber.

A further object of invention is to provide means for performing the above-recited functions in such manner that, in the case more especially of a self-sealing oven-door, such door is free of external pressure during its usually-provided minor movement in parallelism with the surface of the adjacent door-frame prior to its extraction from, and its final seating in, the coking-chamber mouth.

The invention has for further objects such other improvements and such other operative advantages or results as may be found to obtain

in the processes or apparatus hereinafter described or claimed.

The above-stated objects are in general realized by incorporating hereinafter described features of the present improvement in the head of a door-handling machine such, for example, as that shown in the present inventor's U. S. Patent No. 2,182,494, issued December 5, 1939, to Koppers Company and which has provision to grasp and to extract a coke-oven door from a coking-chamber and to elevate and to slue the same sidewise before returning it to the mouth of a coking-chamber by execution of the same said series of movements in reverse sequence.

15 According to the present invention, the door-head mechanism of a door-handling machine is equipped with resilient control-means that is responsive to those usual operative movements of door-handling equipment during the removing and returning of coke-oven doors to coking-chambers. This said resilient control-means is provided with terminal forked members that, during the propelling of the door-head mechanism oven-ward, are adapted initially to enter 20 into loosely supporting engagement of the body of a cammed, horizontally-disposed, oven-door latch-bar having a projecting handle, and thereafter with decreasing distance between said mechanism and the oven-door, said resilient control-means is arranged, at spaced intervals and in sequence, to effect first the releasing of a device, also forming a part of said mechanism, that enters into pressure-contact with the said latch-bar handle, to rotate a cammed latching element 25 of the latch-bar about the longitudinal axis of the latch-bar and thus to relieve the pressure of its cammed portion against an oven-door, the said control-means being thereafter arranged to effect a tripping of said device into such grasping 30 engagement of said latch-bar handle that during a subsequent withdrawal of the door-head mechanism from an oven-face, the cammed latching element is thereby rotated in the opposite direction into a position where it again satisfactorily 35 latches the door. When the latch-bar element has, as described, been rotated into loosened position so as to permit removal of the oven-door, the door-head mechanism has advanced sufficiently oven-ward that its therewith integral 40 door-hooks are in position to be brought into engagement with the door for that usual slight lifting of the latter preparatory to its withdrawal from the coking-chamber, such engagement being accomplished by the customary elevating of 45 the door-head mechanism. Initially, this move- 50 55

ment of elevating the door-head mechanism is utilized, according to the instant improvement, for the release of latch-bar locking-jaws that spring into a position intermediate the face of the oven-door and the body of the latch-bar and thereby secure the latter within the above-said forked members of the resilient control-means, and by so doing, also relieve any pressure of the said resilient control-means against the oven-door.

The said integral door-hooks, of the novel door-head mechanism, are so disposed thereon in respect of their co-operating hook-plates on the oven-door that, during its said movement of elevation, its door-hooks travel upwardly a total distance that is at least substantially equivalent to the effective depth to which a latch-bar is retained in its latch-hooks on the adjacent door-frame, and they are further so disposed as to ensure their traversing such distance either before, or at least substantially by the time, they enter into seating-contact with the hook-plates on the oven-door. By reason of this provision requiring elevating of the door-head mechanism the above-stated distance, the latch-bar that has been loosened and secured thereto by the above-described latch-operating features is ensured of automatic disengagement from its latch-hooks by the time the oven-door is itself supported on the door-head mechanism, thereby leaving the oven-door free both of all external pressure and of any interference with the customarily practiced slight raising thereof above the coke-oven floor prior to withdrawal of its refractory plug-portion from the coking-chamber mouth. This withdrawal of the door's refractory plug-portion is then accomplished by moving outwardly from the oven-face the carriage that directly supports the door-head mechanism in the door-handling machine.

The improved door-head mechanism is also provided with other means, described in the hereinabove-mentioned patent of the present inventor, whereby it can be slewed sidewise to turn an oven-door supported thereon into a position where its refractory plug and the edges of its self-sealing frame are more accessible for cleaning after removal from the coke oven.

By repeating in their reverse sequence the above-described movements and operations of the said features of the novel door-head mechanism, a removed coke-oven door can be easily returned to a coking-chamber and can be tightly relatched into operating position.

The present improvements in the described apparatus make it advantageously expedient simply and effectively and solely by mechanical means, to remove coke-oven doors from, and to return them to, coking-chambers when their latching means are of the described type, and the delineated operative results are realizable without providing for the door-head mechanism, as a whole, movements other than those long employed in the art of coke-oven door-handling and consisting of raising and lowering the door and of moving it backward and forward at the oven-face. The construction, the simplicity of operation, and the advantages of this novel apparatus will be more clearly understood by reference to its following more detailed description made with the assistance of the accompanying drawings.

In the accompanying drawings forming a part of this specification and showing for purposes of exemplification a preferred apparatus and

method in which the invention may be embodied and practiced but without limiting the claimed invention specifically to such illustrative instance or instances:

Fig. 1 is an elevational view, from its side opposite the battery-face, of a door-handling machine embodying the present improvements in door-head mechanisms and also showing diagrammatically in dotted lines the position in the machine assumed by a coke-oven door that has been removed thereby from a coking-chamber and slewed sidewise for its cleaning;

Fig. 2 is a plan view of the door-handling machine shown in Fig. 1;

Fig. 3 is an enlarged side elevational view of the present improved door-head mechanism along with its carriage for moving it forward and backward at an oven-face, and shown embodied in the door-machine of Figs. 1 and 2, some parts being removed and other parts being illustrated in section more clearly to show the arrangement and operation of the mechanism's interior features;

Fig. 4 is a view along the line IV—IV of Fig. 3 showing the spiral race, formed on the outer surface of the housing for the threaded column, and whereby the door-head mechanism is slewable sidewise when said column is rotated;

Fig. 5 is a development view of the figure shown in Fig. 4;

Fig. 6 is an enlarged view of features of invention as disposed at the upper part of the door-head mechanism for operating the thereto adjacent cammed latch-bar of an oven-door, according to the improvement, and showing said features and their relative arrangement in improved detail;

Fig. 7 is a view taken along the line VII—VII of Fig. 3;

Figs. 8 and 9 are horizontal sections taken respectively along the lines VIII—VIII and IX—IX of Fig. 3;

Figs. 10 to 14 are simplified diagrammatic sectional views in elevation arranged to show the progressive relative changes in positions of the latch-operating features of the door-head mechanism during one complete cycle of its operation in unlatching and removing a coke-oven door from its coking-chamber and thereafter returning the same to its latched position therein; and

Fig. 15 is an enlarged perspective view of some of the essential features of the latch-operating unit located at the lower part of the door-head mechanism and showing in greater detail their design, construction, and relative arrangement, certain parts having been omitted and others fragmentarily indicated in the interest of clarity.

The same characters of reference designate the same parts in each of the views of the drawings.

Referring now to the drawings: the type of coke-oven latch-bar for the automatic operation of which the present improvement in door-handling machines has been developed is shown with special clarity in the drawings of Figs. 6 and 15; it comprises a rugged bar that is non-integral with the oven-door and that is of sufficient length to span the same and to repose with its opposite ends in latch-hooks which are affixed to the adjacent door-frame and that is provided with a

handled, median cam-member which may be either rigidly or rotatably mounted on said bar, the cam-member being so disposed that, by its rotation in opposite directions, it is operative to establish or to release pressure between said door-hooks and the oven-door, thereby respectively

creating or relieving sealing-pressure contact between the sealing-edge of a door and its door-frame. It is also clearly apparent from said figures that a latch-bar of the described type must be, for its effective use, lifted out of and lowered into the latch-hooks independently of movement of the associated oven-door respectively before and after the door is removed from and restored to the coking-chamber.

The instant improved door-handling machine 10 shown in Fig. 1 is adapted for use at the coke-side of a coke-oven battery and is mounted on tracks 11 whereby it can be propelled along the operating-bench, usually located at that battery side, by any preferred means arranged to turn wheels 12 of its supporting truck 13. In the present embodiment, the said wheels 12 are driven by an electric motor 14 that operates through reducing gear 15 and a pinion. Lever 16 forms a part of the braking system for the motor 14 and transmits an hydraulic impulse, occasioned in hydraulic cylinder 17 by a pressure applied to brake-pedal 18, to a pair of brake-shoes 19 that are responsive to said impulse to apply a pressure on the driving shaft of motor 14.

The door-handling machine 10 also comprises a carriage 20 of structural steel that is horizontally reciprocative, transversely of the truck 13 of said door-handling machine, on wheels 21 that travel in tracks 22 therefor, this horizontal reciprocatory movement of the carriage 20 serving to advance the same toward or to withdraw it from the face of an oven-door of a battery of horizontal coke ovens. The lower supporting framework 23 of said carriage 20, that directly supports the carriage-propelling wheels 21 also serves as a base for the rugged, vertically disposed mast 24 that carries many of the present features of invention for operating coke-oven doors. By means of motor 25, operating through torque-coupling 26, gear-reducer 27, coupling 28, bell-crank 29, and the lever-system comprising, link 30, shorter and longer links respectively 31, 33, that are attached to opposite ends of shaft 32, and the spring-plunger link 34 which is rotatably attached directly to mast 24, said carriage 20 is reciprocated longitudinally of a coking-chamber on its said wheels 21. The resilient link 34 serves as a safety device to prevent damage to motor 25 or features of invention attached to the door-head mechanism by functioning as a buffer that permits normal travel of other said members of the actuating system for reciprocating carriage 20 even though the distance said carriage must travel forward to establish contact with all the oven doors of the battery may vary from door to door because of minor variations in their alignment. Trip 35 attached to the lower part of mast 24 is also a safety feature in that it permits propelling of truck 13 along the battery front only when carriage 20 is in fully retracted position thereof; it functions as follows: when said carriage starts to move forward toward the battery-face, by rotation of motor 25, said trip 35 allows handle 36 of cut-out switch 37 to assume a position whereby it stops flow of electric current to motor 14 which is only re-established when the carriage has been returned to its retracted position and said trip has again moved said handle 36 into closed-circuit position for motor 14.

The present improved door-head mechanism 38 and the means for vertically reciprocating the same are all supported on carriage 20 of the door-handling machine by means of the mast 24 which for that purpose has cross-arm means 39

located atop thereof; the said cross-arm means 39 is appropriately formed and attached to the mast in a manner to hold in alignment the two heavy I-beams comprising it and also to provide adequate support for electric motor 40. A lateral projection 41 from said cross-arm means serves to support substantially the entire weight of the door-head mechanism 38 which depends therefrom by means of threaded, rotatable column 42 that at its upper end is supported in thrust-bearing 43 which nests in projection 41 of the said cross-arm means. The lower end of said column 42 is rotatably supported in alignment, but without bearing weight, in the lower bearing 44 that is held in a bracket 45 affixed to mast 24. Electric motor 40, operating through a coupling, a worm, and a worm-gear, respectively 46, 47, 48, is arranged to rotate the column 42 around its vertical axis by power delivered to said motor through flexible cable 49 that is of sufficient length to permit unhampered reciprocation of the carriage 20.

Mounted on threaded column 42 is a housing for the whole of said door head, which housing is indicated generally by reference numeral 50. The housing 50 encloses or supports those features of the door-head mechanism of invention that are directly employed in the automatic operating of the door-latches and the handling of the oven-doors themselves. The said door-head housing 50, as clearly shown in Fig. 3, is mounted on threaded column 42 by means of internally-threaded nut 51 that is enclosed within a separate housing compartment 52 therefor formed in the housing 50 for the whole of said door-head. The said nut 51 directly carries all the weight of housing 50 and the divers features of invention the housing supports, and said nut 51 has polygonally-shaped side walls with which the walls of its separate housing 52 correspond, thereby to obviate excessive rotational movement of the nut independently of other features of the door-head mechanism when column 42 is rotated by motor 40; the nut 51 is, however, not rigidly confined in its said housing but is advantageously permitted a degree of floating movement so that it is free without strain to follow minor irregularities or departures from precise alignment of portions of the threaded column. Rotational movement of housing 50 around its supporting column 42 is controlled by means of roller 53, which is pinned to the mast 24, and of a uniquely-contoured co-operative helicoidal race 54 formed on the external surface of that portion of housing 50 which directly surrounds said column 42. Roller 53 is always confined between the side walls of the race 54 and in this wise uncontrolled slueing of the door-head side-wise is obviated. As is clearly apparent by reference to Figs. 3, 4, 5, the upper part of the helicoidal race 54 is provided for a short distance with vertical side-walls so disposed that pressure of roller 53 thereagainst maintains the door-head mechanism turned in alignment with a coking-chamber and in door-grasping position before an oven-door. Below this vertical section, the said side-walls of race 54 veer helicoidally downward until they reach a position at right-angles to their uppermost section; this helicoidal portion of the race's lower side-walls operates by pressure against roller 53, after an oven-door has been removed from a coking-chamber and when the column 42 is being rotated to elevate the door-head mechanism and its attached oven-door, to slue said mecha-

nism and door around as much as ninety degrees to its former position where its sealing edges and refractory plug are more accessible for cleaning. During the raising and the lowering of the door-head mechanism 38, telescopic shield covers 167 at the bottom and top thereof follow its travel to provide a suitable covering for the column and to prevent infiltration of air-borne solids into the working parts inside the door-head.

Those features of the present improvement that are specifically directed to automatic operation of the hereinabove-described type of latch-bar and are adapted to rotate the same, or the latching elements thereof, in opposite directions about their axes and to remove them from and restore them to fixed latch-hooks independently of movement of the associated oven-door, are all formed integrally with the door-head mechanism 38, and as will be manifest from the following description, they are furthermore so operatively adapted to perform these functions that an associated oven-door can freely depend from the usual door-hooks of a door-handling machine during the conventional operations of handling a door.

To this end, said door-head mechanism 38, as clearly shown in Fig. 3 and in the enlarged views of Figs. 6 and 15, is furnished with a plurality of resilient control-members—two each at the upper and the lower parts of said mechanism disposed on opposite sides of its vertical median—and each comprising a rod 55 that is arranged for horizontal plunger-like motion within and under the influence of a circumferentially-discovered coil spring 56 that is itself confined in a fixed casing 57 attached to the inner surface of housing 50 of said door-head mechanism. A longitudinal lateral opening 58 in the inner wall of fixed casing 57 is provided to allow horizontal travel of a trigger-plate 59 that is affixed to a said rod 55 and serves during horizontal reciprocatory movement of the latter and of the door-head mechanism to release and to return to operating position, in sequence, latch-operating features hereinafter described.

Affixed to the outer end of each of said spring-actuated rods 55 of the resilient control-members and in vertical alignment thereon is a roller-wheel 60 and a forked-member 61, the former being disposed, during movement of the door-head mechanism toward the oven-door, to enter into pressure-contact with the vertical surface of a large boss 62 that is integral with the supporting-back of the oven-door whereas the latter, at the same time, enters into supporting engagement with the body of the latch-bar 69; since, as above stated, there is provided two such spaced rods 55 adjacent both the top and the bottom of the door-head mechanism, as is more clearly evident in Fig. 15, they supportably secure a latch-bar at at least two points along its length during its removal from and return to latching position in the latch-hooks.

The device 63 of the door-head mechanism is the medium that directly serves to move the cammed element of a latch-bar about the longitudinal axis of the latch-bar, in opposite directions according to the invention. This device is a rather intricately-formed casting having a hub-portion 64 whereby it is pivotally mounted by shaft 65 to opposite side-walls of the door-machine housing 50. Projecting from the battery-side of said hub 64 is a bracketed section that terminates in a crooked or J-shaped portion 66 which, when said device is accorded rotary

movement about its shaft 65, by means herein-after described that are responsive to the horizontal reciprocatory motion of the door-head mechanism, is operative, firstly, to press on handle 67 of the cammed element 68 of latch-bar 69 and to move said element about the longitudinal axis of the latch-bar in the direction of the door to loosen said bar at the same time the door-head mechanism is moving in the same direction, and is thereafter operative, by the said rotary movement of device 63, to tip into such engagement with the end of handle 67 that the cammed element is pulled into latched position at the same time the door-head mechanism during its said reciprocatory motion is withdrawn from the face of the oven-door.

Integral with hub 64 of latch-operative device 63, but arranged on that side opposite its said J-shaped portion 66, are formed a pair of levers 70, 71, of unequal length so spaced apart that they are individually operable for rotary movement of device 63 by only one of the trigger-plates 59 of the thereto adjacent pair of rods 55 of the above-described resilient control-means, the axis of the former and longer lever, 70, extending nearly horizontally outwardly from said hub whereas the axis of the latter and shorter lever, 71, extends about horizontally for a short distance and then abruptly turns to form a substantially right-angled bend. The said longer lever 70 is rotatably-mounted at its outer end, by a pin, in clevis 72 which is resiliently-supported in housing 50 of the door-head mechanism by means of rod 73 that is axially-disposed in a coil-spring 74, the latter being confined at its one end by a bracket-wall, that is formed inside the said housing, and at its opposite end by washer 75 and nut 76 threaded on the terminus of rod 73. A rugged tooth 77, medially projecting from the otherwise linear surface of lever 70, is disposed to co-act with notches 78 in the adjacent surface of catch-block 79, whereby temporarily to arrest and retain latch-operating device 63, during its stepwise rotary motion about shaft 65, at preferred operating positions in part determined by the positions that are assumed by said catch-block 79 and which are themselves controlled by lever-lock bar 80 on which said catch-block is mounted.

50 The upper and lower lever-lock bars 80 are pivotally mounted to the walls of housing 50 by means of their hubs 81 and of a shaft 82 and they are independently rotatable on said shaft and, as shown in Figs. 7 and 15, are each a composite of two spaced bars for a portion of their length, a catch-block 79 being mounted therebetween. These two lever-lock bars are not disposed in true alignment in the door-head mechanism but are off-set, as shown in Figure 7, and are thus independently rotatable to move their catch-blocks 79 into and out of engagement with their teeth 77, as their function in said mechanism requires. By means of clevis 83, pin 84, and rod 85, each of the lever-lock bars communicates with a coil-spring 86 that is confined between an interior wall of housing 50 and a washer 87 and nut 88 threaded on the terminus of rod 85. Pressure of a trigger-plate 59 against the free end of a lever-lock bar 80 causes outward rotation of said bar which in turn moves its catch block 79 out of engagement with its tooth 77 and thus also compresses the associated coil-spring 86; subsequent expansion of said coil-spring serves to rotate the bar 80 to its initial upright position in the door-head mechanism.

55 60 65 70 75 80 85 90

when pressure of said trigger-plate 59 against the latter is released by movement of the door-head mechanism away from the door, and simultaneously the attached catch-block 79 is moved to a position where it can re-engage tooth 77 of lever 70. Adjustable screw 89 provides means for accurately adjusting the point at which a lever-lock bar 80 is engaged and released by trigger-bar 59 during horizontal reciprocatory movement of the door-head mechanism.

As afore-indicated, when the door-head mechanism of the door-handling machine is moved forward into contact with the face of an oven-door, the body of a latch-bar 88 is loosely engaged by the two forked members 61 located at the ends of spring-actuated rods 55 of the resilient control-members. These forked members are arranged supportably to engage a latch-bar but are not fashioned to grab and to lock it to the door-head mechanism for that period when the latch-bar, during its manipulation, is lifted from the latch-bar hooks 90 and the oven-door is removed from its coking-chamber. For accomplishing this purpose, therefore, the door-head mechanism is, according to the invention, provided at its upper and lower parts, with latch-bar locking-jaws each comprising a pair of spaced hooks 91 that fork from a single lever-handle 92 which is pivotally supported by a shaft 93 to opposite walls of housing 50, the lever-handles 92 of the upper and the lower hooks 91 of the locking-jaws being so interconnected by tie-rod 94 that said locking-jaws are simultaneously moved in opposite directions. This contrary movement of said locking-jaws is produced by including said tie-rod 94 in a lever-system comprising itself and the short link 95 which is pivotally attached to lever-handle 92 of the lower locking-jaw, the said link 95 being also resiliently supported in the door-head mechanism by a rod 96 that by means of a terminal washer and nut, respectively 97, 98, confines coil-spring 99 between said member 97 and a portion of the wall of said mechanism's housing. Trigger-post 100 that is fixed to the outer end of bracket 45, which also supports bearing 44 for the lower end of threaded column 42, is disposed, when the door-head mechanism is in lowered position on said threaded column, to press against the end of lever-handle 92 of the lower latch-bar locking-jaw, thereby maintaining both the upper and lower locking-jaws in unlocked position and also compressing the coil-spring 99. When, however, housing 50 is elevated by rotation of threaded column 42, pressure of the fixed trigger-post 100 against the outer end of member 92 is diminished and coil-spring 99 starts to expand and moves the locking-jaws 91 into position between the face of the adjacent oven-door and the latch-bars and ultimately said coil-spring expands sufficiently for the previously-loosened latch-bars to be rigidly grasped, between forked members 61 and the said locking jaws, whereby they become temporarily secured to the door-head mechanism and can be lifted out of latch-hooks 90 independently of any movement of the oven-door by further elevation of the housing 50 on threaded column 42. Advantageously, spring-pressure of the locking-jaws against the body of the latch-bars also indirectly relieves the oven-door of all pressure of roller-wheels 61 against their co-acting bosses 62 thereon, so that the oven-door is free of all external sealing-pressure when the latch-bars have been removed from the latch-hooks and, in result, the flexible sealing-edge 101

of the oven-door can, during the operation of removing and restoring a coke-oven door to a coking-chamber, be moved vertically in contact with the door-frame 102 the customary short distance, before actual extraction of the oven-door from the coking-chamber, without danger of injury to said flexible sealing-edge.

The upper and lower door-hooks, respectively 103, 104, are, as shown in Fig. 3, formed integrally with housing 50 of the door-head mechanism and they project outwardly therefrom sufficiently that, during outward movement of said mechanism, they enter openings 105 in the supporting-back of the oven-door, which in the present instance is of the turtle-back type described and claimed in the hereinabove mentioned copending application of Joseph van Ackeren and wherein the said supporting-back itself also functions as hook-plates for grasping of the door by the door-hooks, such distance that they are in a position, without further outward movement of said door-head mechanism and during its later elevation, to grasp the oven-door by the time the other door-head features have rotated the latch-bars into loosened position; the said door-hooks are also disposed sufficiently below the upper edge of openings 105 that, during the said elevating of the door-head mechanism, the loosened latch-bars will have been both engaged by the locking-jaws 91 and raised until they are emergent from their latch-hooks 90 when the door-hooks have reached lifting-engagement with the said upper edge of openings 105.

When, therefore, the door-hooks 103, 104, have reached lifting-engagement with the oven-door, its cammed latch-bars will have been automatically loosened and locked to the door-head mechanism of the invention and will also have been lifted out of the latch-hooks, and the oven-door will be freely supported on the door-head for extraction from the oven in conformity with established procedure, by moving carriage 20 outward from the battery-face, and, thereafter, by means of the illustrated apparatus, the so-removed oven-door can be further elevated by additional rotation of column 42 and, at the same time, can be slued sidewise by pressure of roller 53 against the walls of helicoidal race 54. Repeating the above operations in the reverse order of the stated sequence will automatically restore the removed oven-door to the coking-chamber and, by the simple movement of withdrawing the door-head mechanism away from the face of the oven-door, the latter will be left in latched and sealed position in the coke oven.

It should be here noted for purpose of clearer understanding of the apparatus of the drawings that the levers 70, 71, of the latch-operating devices 63 are disposed on their hubs 64 in opposite order as between the said device at the top and the bottom of the door-head mechanism so as more simply to accommodate their operative features in the door-head housing 50.

A short description of the movements and of the operative results produced by the above-described features of apparatus will assist understanding of their workings and emphasize the simplicity with which the instant mechanism as a unit automatically performs the described sequence of latch-bar operations without requiring manipulations of a door-head mechanism other than those customarily employed in operating coke-oven doors. Such description will be made by reference more particularly to Figs. 10 to 14.

Let it be assumed that the door-handling ma-

chine 10 has been propelled along tracks 11, at the face of a coke-oven battery, by motor 14 and that its carriage 20 has been placed in proper position in front of the coke-oven door that is to be removed from a coking-chamber. The cammed member 68 of the latched latch-bar 69 will be found to be so turned that that surface thereof at the end of its longer axis is pressing against its bearing plate 106 affixed to the face of the oven-door and the body of the latch-bar will be pressing against the outer surface of the recess in the latch hooks 90. The handles of the said cammed members 68 on the upper and the lower latch-bar will be found to be directed respectively downwards and upwards, as shown in Figs. 10 to 14.

The relative positions of the latch-operating features of the door-head mechanism will be in substantially the relative positions shown in Fig. 10 in which they were left after restoring and latching, in sealed position, the self-sealing oven-door of the just previously pushed coking-chamber.

As carriage 20 is advanced in the direction of the oven-door by motor 25, the spaced roller-wheels 60, of which each is affixed to the end of a rod 55 comprising the resilient control-members at the upper and lower portions of the door-head mechanism, first come into pressure-contact with bosses 62 on the face of the oven-door and at the same time the similarly spaced forked-members 61, also carried on the ends of said rods 55, supportably engage the body of the upper and the lower latch-bar 69, as shown in Figs. 10 and 15, at two spaced points therealong. Further advancing of said carriage in the direction of the door, causes trigger-plates 59, that are attached to rods 55, to compress coil-springs 56, thereby permitting the other features of the door-head mechanism to advance relative to the now stationary rods 55 and to move closer to the face of the oven-door. As those trigger-plates 59 which are directly behind the shorter levers 71 of the devices 63 for operating the cammed elements of the latch-bars (see Fig. 15), start to compress their associated coil-springs 56, these particular trigger-plates leave previous contact with said levers 71 and can no longer interfere with subsequent rotary movement of devices 63 about their shafts 65. Each said device 63 is, however, still rigidly supported to resist rotational pressure because the tooth 77 of its longer lever 70 is still locked in its nearest notch 78 on the surface of catch-block 79. With further advance of the door-head mechanism toward the face of the oven-door, the vertically disposed leg of the J-shaped portion 66 of a said device 63 presses against handle 67 of the cammed element 68 of the latch-bar and rotates the same into position where it no longer presses against its bearing-plate 106 on the oven-door, as shown in Fig. 11, and the associated latch-bar then lies loosely in latch-bar hooks 90 and sealing-pressure on the door is relieved. Rotation of the cammed elements of both latch-bars into loosened position having been thus effected, those trigger-plates 59, which have, in the interim, been compressing the coil-springs 56 adjacent to the longer levers 70 of the cam-operating devices 63, have established contact with the ends of lever-lock bars 80 which they cause to rotate away from the oven-door face on their shafts 82, thereby compressing coil-springs 86 and each also releasing the tooth 77 of its longer lever 70 from locked position in

5 catch-block 79, whereupon the associated coil-spring 74 expands and causes a cam-operating device 63 to rotate on its shaft 65 and the shorter leg of its J-shaped portion 66 thus to pass behind a handle 67 of cammed element 68 so that said handle is actually engaged by the J-shaped portion 66 and during a subsequent withdrawal of the door-head mechanism away from the oven-door, the device 63 is held by coil-spring 74 in position to rotate the cammed element into latch-tightening position. The relative positions of the various features of the invention at this juncture are clearly shown in Fig. 12 to which reference will also show that door-hooks 103, 104, have sufficiently entered openings 105, in the supporting-back of the turtle-back oven-door, that elevating of the door-head mechanism will cause them to enter into lifting engagement of the door.

20 The cammed elements of the latch-bars having been rotated into loosened position, the door-head mechanism is advanced no further toward the oven-door, and motor 40 is started to rotate threaded column 42 in that direction which elevates the door-head mechanism 38 thereon and, as it rises, pressure of fixed trigger-post 100 against lever-handle 92 of the lower locking-jaw hooks 91 is gradually relieved, the coil-spring 99 thereupon can expand and thereby exerts such tension on tie-rod 94 that the locking-jaw hooks 91 are moved into engagement of the latch-bars at their sides adjacent the oven-door, thereby grasping the latch-bars and temporarily supporting them on the door-head mechanism. Continued elevation of the door-head mechanism on column 42 lifts the latch-bars out of engagement with their latch-bar hooks 90 by the time that the door-hooks 103, 104, have reached lifting-engagement with the oven-door, in which relative position the various said parts are now shown in Fig. 13. The oven-door now freely depending from the door-hooks is slightly elevated above the floor of the coking-chamber, motor 40 is stopped, and the oven-door is withdrawn from the coking-chamber by moving carriage 20 outwardly from the battery face by rotation of motor 25. Following extraction of the oven-door from its coking-chamber, motor 40 is again started, and the door-head mechanism, including 30 the loosened and lifted latch-bars and the thereon-supported oven-door, is further elevated on threaded column 42 until by pressure of roller 53 against the walls of helicoidal race 54, the door-head and its attached said features are slewed 40 sidewise, as above described, for easy cleaning of the refractory plug and sealing-edges. The oven-door has now taken its relative position in the door-handling machine diagrammatically shown in dotted lines in Fig. 1.

45 In replacing the oven-door, motor 40 is again started and column 42 is rotated in that direction which lowers the oven-door and simultaneously slewes it back into position in front of the mouth of the coking-chamber. Motor 40 is then stopped, motor 25 is re-started and carriage 20 is advanced toward the coking-chamber mouth until it is in position in the door-frame with its sealing-edge in contact with the latter, whereupon motor 25 is stopped. Motor 40 is again started and the door is lowered into its final seating on the oven-sole by further rotation of said column 42. Continuing the rotation of said column lowers the door-head mechanism relative to the oven-door, thereby simultaneously lowering door-hooks 103, 104, from lifting-

engagement with the door and also lowering the cammed latch-bars 69 into place in their latch-hooks 80. Still further rotation of column 42 brings lower lever-handle 92 of the latch-bar locking-jaws 91 into re-engagement with fixed trigger-post 100, thereby compressing coil-spring 89 and rotating said locking-jaws into open position. The latch-bars are thus disengaged from the door-head mechanism and lie loosely cradled in the latch-bar hooks 80 with, however, the handles 67 of their cammed elements still in engagement with the J-shaped portions 66 of their latch-operating devices 63, in the position clearly shown in Fig. 6. Motor 40 is again stopped when these operations have been completed, and there remains only to be accomplished the rotation of the cammed elements 68 into their door-sealing position. This latter operation is automatically accomplished during withdrawal of carriage 20 from the face of the oven-door by motor 25. As the carriage recedes from the door, the J-shaped portions 66 of devices 63 pull on handles 67 of the cammed elements 68 and rotate the latter into sealing-pressure contact with bearing-plates 106 on the door. As the distance between the oven-door and the door-head mechanism increases during withdrawal of the latter from the face of the door, the tension of the pull of devices 63 on the latch-handles also increases, thereby compressing coil-springs 74 and allowing said devices 63 to rotate on their shafts 65; when the tension of the devices 63 on the latch-handles exceeds a predetermined value adequate to tighten the cammed elements 68, springs 74 are sufficiently compressed to permit the J-shaped portions 66 of devices 63 to rotate out of engagement with said latch handles (see Fig. 14). While this movement is taking place, those trigger-plates 59, that actuate the lever-lock bars 80, have been moved away, by expansion of springs 56, from the ends of the same and they have been restored to vertical position by rotation on their shafts 82, by expansion of coil-springs 86, carrying with them the catch-blocks 79, and the latter are thus restored to those positions where teeth 71 of levers 70 enter into engagement with the more remote of the recesses on the adjacent surfaces of said catch-blocks, thereby locking the devices 63 at the top and bottom of the door-head mechanism in substantially their original positions and retaining their actuating springs 74 under that compression required to rotate the devices 63 into engagement with the latch-handles of the next door to be removed. Just prior to complete withdrawal of the door-head mechanism from contact with the face of the replaced oven-door, those trigger-plates 59, that actuate the shorter curved levers 71 of latch-operating devices 63, are pressed by their coil springs 56 against the outer surfaces of said shorter levers, thereby rotating the devices 63 a slightly increased amount away from the face of the door so as to provide that added clearance therefor that minor variations in the lengths or positions of the ends of the latch-bar handles 67 of successive oven-doors of the battery may require. During this final added rotation of devices 63, the teeth 71 of their longer levers 70 are moved to locking position in their nearest adjacent recesses 78 of catch-blocks 79 to assure that said devices retain this added movement. The various features of the improved door-head mechanism have now resumed their original relative positions and

are prepared to unlatch and re-latch the next door to be removed.

As is now manifest from the above-given, all the described workings of the door-head features 5 are automatically co-operative and take place in rapid sequence and coke-oven doors equipped with latch-bars of the described type can be removed from and restored to coking-chambers by automatic mechanical means requiring no 10 operative movements of the door-handling machine other than those long employed and required for the purpose.

The invention as hereinabove set forth is embodied in particular form and manner but may 15 be variously embodied within the scope of the claims hereinafter made.

I claim:

1. Coke-oven apparatus for manipulating doors of horizontal coke ovens, said apparatus comprising a door-head mechanism that is longitudinally and vertically reciprocative in respect of a coking-chamber both to operate the latches of and to remove and to restore the oven-door of a coking-chamber, said door-head mechanism comprising: a device adapted to produce rotary movement of a latching element of a latch-bar about its longitudinal axis in opposite directions alternately in accordance with the direction of movement of the door-head mechanism in its 25 said horizontal reciprocatory movement, thereby to loosen and to tighten said latch-bar; means operative to support said latch-bar on said door-head mechanism independently of its associated coke-oven door during an interval between said 30 opposite rotary movements of the latch-bar, so that said latch-bar is vertically reciprocative separately of said door in unlatching and latching the same; and other means that are operative vertically to reciprocate said latch-bar and its 35 said supporting means independently of its associated coke-oven door for disengagement of the latch-bar from, and re-engagement in, latch-hooks therefor.

2. Coke-oven apparatus for manipulating doors 45 of horizontal coke ovens, said apparatus comprising a door-head mechanism that is longitudinally and vertically reciprocative in respect of a coking-chamber both to operate the latches of and to remove and to restore the oven-door of a coking-chamber, said door-head mechanism comprising: a device adapted to produce rotary movement of a latching element of a latch-bar about its longitudinal axis in opposite directions alternately in accordance with the direction of movement of the door-head mechanism in its said 50 horizontal reciprocatory movement, thereby to loosen and to tighten said latch-bar; and means that are adapted graspingly to support said latch-bar on said door-head mechanism and to reciprocate said latch-bar vertically independently of its associated coke-oven door for disengagement from and re-engagement in latch-hooks for said latch-bar.

3. Coke-oven apparatus for manipulating doors 65 of horizontal coke ovens, said apparatus comprising a door-head mechanism that is longitudinally and vertically reciprocative in respect of a coking-chamber both to operate the latches of and to remove and to restore the oven-door of a coking-chamber, said door-head mechanism comprising: a device adapted to utilize the force of 70 movement of the door-head mechanism in its horizontal reciprocative movement towards and away from the door to produce rotary movement of a latching element of a latch-bar about the

longitudinal axis of the latch-bar in opposite directions to thereby loosen and to tighten the latch-bar; and means disposed to grasp and support said latch-bar on said door-head mechanism independently of attachment of the latch-bar to said door for movement of said latch-bar together with the door, and to reciprocate said latch-bar vertically independently of movement of its associated coke-oven door.

4. Coke-oven apparatus for manipulating doors of horizontal coke ovens, said apparatus comprising a door-head mechanism that is horizontally reciprocative to operate the latches of and to remove and to restore the oven-door of a coking-chamber, said door-head mechanism comprising: a device adapted to utilize the force of movement of the door-head mechanism in its horizontal reciprocative movement towards and away from the door to produce rotary movement of a latching element of a latch-bar about the longitudinal axis of the latch-bar in opposite directions alternately in accordance with the direction of movement of the door-head mechanism in its said horizontal reciprocative movement, thereby to loosen and to tighten said latch-bar; and means that are adapted to grasp and support said latch-bar and to reciprocate the same vertically independently of movement of its associated coke-oven door for disengagement from and re-engagement in latch-hooks for said latch-bar.

5. Coke-oven apparatus for manipulating doors of horizontal coke ovens, said apparatus comprising a door-head mechanism that is horizontally and vertically reciprocative in front of a coke-oven door to operate the latches of and to remove and to restore said coke-oven door of a coking-chamber, said door-head mechanism comprising: a device that is responsive to said horizontal reciprocatory movement of said door-head mechanism in front of an oven-door alternately to push and to pull a latching element of an oven-door latch-bar about the longitudinal axis of the latch-bar, thereby alternately to loosen and to tighten said latch-bar between its latch-hooks and the associated oven-door; and means that are responsive to said vertical reciprocatory motion of said door-head mechanism to raise the loosened latch-bar from and to restore the same to its said latch-hooks independently of vertical movement of said oven-door.

6. Coke-oven apparatus for manipulating doors of horizontal coke ovens, said apparatus comprising a door-head mechanism that is horizontally reciprocative in front of a coke-oven door to operate the latches of said door and has also means adapted for grasping and releasing said door, said door-head mechanism comprising: a device that is responsive to said horizontal reciprocatory movement of said door-head mechanism in front of an oven-door to push and to pull a latching element of an oven-door latch-bar about the longitudinal axis of the latch-bar during respectively the forward and backward movement of said door-head mechanism in its horizontal reciprocatory motion and thereby respectively to loosen and to tighten said latch-bar between its latch-hooks and the associated oven-door; means that are vertically reciprocative to grasp and release said oven-door; and other means that are adapted for vertical reciprocation to raise a loosened latch-bar from and to restore the same to its latch-hooks without grasping said oven-door.

7. Coke-oven apparatus for manipulating doors of horizontal coke ovens, said apparatus comprising

5 ing, a door-head mechanism that is horizontally reciprocative in front of a coke-oven door to operate the latches of said door and has also means adapted for grasping and releasing said door, said door-head mechanism comprising: a device that is responsive to said horizontal reciprocatory movement of said door-head mechanism in front of an oven-door alternately to push and to pull a latching element of an oven-door latch-bar about the longitudinal axis of the latch-bar, thereby alternately to loosen and to tighten said latch-bar between its latch-hooks and the associated oven-door; means that are vertically reciprocative to grasp and release said oven-door; and other means that are adapted for vertical reciprocation to raise a loosened latch-bar from and to restore the same to its latch-hooks without grasping said oven-door.

20 8. Coke-oven apparatus for manipulating doors of horizontal coke ovens, said apparatus comprising a door-head mechanism that is adapted to remove and to restore the oven-door of a coking-chamber and is horizontally reciprocative to operate the latches for said oven-door, said door-head mechanism comprising: a resilient member that is adapted to apply pressure to the oven-door and to remain substantially stationary during horizontal reciprocation of said door-head mechanism in front of said oven-door, and a resiliently 25 rotatable device that is operatively responsive to demands of said resilient member, said rotatable device being adapted, during movement of said door-head mechanism in the direction of said oven-door, both to press on a latching element of a latch-bar of said oven-door to rotate the same about its longitudinal axis, thereby to loosen said latch-bar, and thereafter to be released in response to said resilient member into resilient engagement with said latching element so as to rotate said device in the opposite direction to tighten said latch-bar, said rotatable device being further adapted, during motion of the door-head mechanism away from said door to pull said latching element of said latch-bar into its latch-tightening 30 position and thereafter to be rotated into disengagement of said latching element followed by its arrestment by means including said resilient member.

50 9. Coke-oven apparatus for manipulating doors of horizontal coke ovens, said apparatus comprising a door-head mechanism that is adapted to remove and to restore the oven-door of a coking-chamber and is horizontally reciprocative to operate the latches for said oven-door, said door-head mechanism comprising: a resilient member that is adapted to apply pressure to the oven-door and to remain substantially stationary during horizontal reciprocation of said door-head mechanism in front of said oven-door; a resiliently 55 rotatable device that is operatively responsive to demands of said resilient member, said rotatable device being adapted, during movement of said door-head mechanism in the direction of said oven-door, both to press on a latching element of a latch-bar of said oven-door to rotate the same about its longitudinal axis, thereby to loosen said latch-bar, and thereafter to be released in response to said resilient member into resilient engagement with said latching element 60 so as to rotate said device in the opposite direction to tighten said latch-bar, said rotatable device being further adapted, during motion of the door-head mechanism away from said door, to pull said latching element of said latch-bar into its latch-tightening position and thereafter to be 65 70 75

rotated into disengagement of said latching element followed by its arrestment by means including said resilient member; and means that are adapted for vertical reciprocation to raise the loosened latch-bar from and to restore the same to its latch-hooks without grasping said oven-door.

10. Coke-oven apparatus for manipulating doors of horizontal coke ovens, said apparatus comprising a door-head mechanism that is horizontally reciprocative in front of an oven-door to operate the latches of and to remove and to restore said coke-oven door of a coking-chamber, said door-head mechanism comprising: a resilient member that is adapted to apply pressure to the oven-door and to remain substantially stationary in respect of the same during horizontal reciprocation of said door-head mechanism; a resiliently rotatable device that is operatively responsive to demands of said resilient member, said rotatable device being adapted, during movement of said door-head mechanism in the direction of said oven-door, both to press on a latching element of a latch-bar of said oven-door to loosen said latch-bar and thereafter to be released by said resilient member into resilient engagement with said latching element for pulling the same into latch-tightening position, said rotatable device being further adapted, during motion of said door-head mechanism away from said door, to pull said latching element into its latch-tightening position and thereafter to be rotated into disengagement of said latching element followed by its arrestment by means including said resilient member; and means adapted for vertical reciprocation to raise a loosened latch-bar from and to restore the same to its latch hooks and also to remove pressure of said resilient member on said oven-door without grasping said door.

11. Coke-oven apparatus for manipulating doors of horizontal coke ovens, said apparatus comprising a door-head mechanism that is horizontally and vertically reciprocative in front of an oven-door to operate the latches of and to remove and to restore said coke-oven door of a coking-chamber, said door-head mechanism comprising: a resilient member that is adapted to apply pressure to the oven-door and to remain substantially stationary in respect of the same during horizontal reciprocation of said door-head mechanism; a resiliently rotatable device that is operatively responsive to demands of said resilient member, said rotatable device being adapted, during movement of said door-

5 10 15 20 25 30 35 40 45 50

head mechanism in the direction of said oven-door, both to press on a latching element of a latch-bar to loosen the same and thereafter to be released by said resilient member into resilient engagement with said latching element for pulling the same into latch-tightening position, said rotatable device being further adapted, during motion of said door-head mechanism away from said door, to pull said latching element into its latch-tightening position and thereafter to be rotated into disengagement of said latching element followed by its arrestment by means including said resilient member; hook means adapted to grasp said oven-door during said vertical reciprocation of said door-head mechanism; and other means operative by said vertical reciprocation of the door-head mechanism to secure thereon a thereby-loosened latch-bar and also to relieve pressure of said resilient member on the oven-door and to raise said latch-bar from and to restore the same to latch-hooks without grasping said oven-door.

12. Coke-oven apparatus for operating a latch-bar for a coke-oven door, comprising: a door-head mechanism reciprocative toward and away from a coke-oven door; and a plurality of latch-actuating means mounted on said door-head mechanism; one of said latch-actuating means being arranged to utilize the force of the head-mechanism on its movement toward the door to press on a latching-element of a latch-bar for the door to loosen it, and another of said latch-actuating means being arranged to utilize the force of the head-mechanism on its movement away from the door to pull the latching-element into latch-tightening position, the latch-tightening latch-actuating means being mounted on the head-mechanism to clear the latching element as the latch-loosening latch-actuating means is 40 moving into engagement with the latching-element on the latch-loosening movement of the head-mechanism toward the door, and said latch-tightening latch-actuating-means being so mounted on the door-head mechanism as to be 45 moved relative to the latching-element to be positioned into its pulling position after clearing the latching-element, but on movement of the head-mechanism away from the door in latching the same the latch-tightening latch-actuating means is moved so as to again clear the latching-element after the latch-tightening latch-actuating-means has pulled the latching-element into its latch-bar tightening position.

PAUL HOWARD LAVELY.
